UNITED STATES PATENT OFFICE.

HARRY F. PERKINS, OF SCHENECTADY, NEW YORK, ASSIGNOR TO GENERAL ELECTRIC COMPANY, A CORPORATION OF NEW YORK.

SPACE SIGNALING SYSTEM.

1,074,456.

Specification of Letters Patent. Patented Sept. 30, 1913.

Application filed July 29, 1909. Serial No. 510,196.

To all whom it may concern:

Be it known that I, HARRY F. PERKINS, a citizen of the United States, residing at Schenectady, in the county of Schenectady, State of New York, have invented certain new and useful Improvements in Space Signaling Systems, of which the following is a specification.

My invention relates to sending instruments for space signaling, or any other similar class of apparatus in which it is necessary to frequently interrupt heavy dynamic currents.

In high-powered wireless telegraph stations it is frequently customary to work with currents of forty to fifty kilowatts, or even greater amounts of energy. As is to be expected, the rapid interruption of heavy currents when sending messages introduces considerable difficulty. Heretofore oil switches have been used for this purpose, but the continued and severe arcing rapidly destroys the metallic contacts.

Two kinds of currents are employed in space signaling; namely, alternating currents, which, as is well known, rise and fall between zero and a maximum value and reverse in polarity; and pulsating currents, which rise and fall between minimum and maximum value without reversing in polarity. These two kinds of currents will hereinafter be referred to under the general term of periodic currents.

According to my invention, a mercury vapor device is included in the main circuit, by which, as will be explained, the circuit is broken when sending messages.

The mercury-vapor device comprises essentially a mercury electrode and a co-operating electrode, both contained in an exhausted envelop, and through which, as is well known, a current will readily flow when an arc has once been started. The arc breaks when the impressed voltage falls below a certain minimum value, thus opening the circuit. This mercury-vapor device is provided with an auxiliary starting device for rendering the space between the mercury electrode and the co-operating electrode conductive. In the present instance the starting device consists of a supplemental elec-

trode, which draws an arc maintained by direct current. As its operating current is small the circuit containing the auxiliary arc can be interrupted at will by the operator with use of a suitable switch, such as an ordinary telegrapher's key. As long as the auxiliary arc is maintained the main arc is kept alive; but when the auxiliary arc is interrupted by opening its circuit the main arc breaks when the voltage of the periodic current falls below the minimum value necessary to maintain it.

Preferably current passing through the vapor device and interrupted thereby is of low voltage and high amperage, and is transformed to any desired higher voltage before being sent out as electromagnetic waves.

My invention will be more readily understood by reference to the following drawing, in which—

Figure 1 is a simple diagram of circuits, showing the arrangement in which a half wave of an alternating current is utilized. This arrangement, therefore, furnishes a pulsating current. According to the arrangement shown in Fig. 2, both half waves of an alternating current are utilized by the use of two mercury vapor devices. Fig. 3 is a somewhat modified arrangement, similarly utilizing both half waves of an alternating current using but one mercury-vapor device. Fig. 4 is a cross-sectional view, showing details of the mercury-vapor device; and Fig. 5 is a sectional detail view of the auxiliary starting electrode.

Referring to Fig. 1, it will be seen that the mercury-vapor device 1 is in series with the secondary of a step-down transformer 2 and the primary of a step-up transformer 3. As shown diagrammatically in this figure, the mercury-vapor device contains a small amount of mercury 4, which forms the negative electrode. The positive electrode 5 consists of graphite, or other suitable material. It is insulated from the negative electrode 4. The auxiliary electrode 6, of similar construction to main electrode 5, is ordinarily in contact with the mercury electrode 4, but is lifted out of contact therewith by the solenoid 7, which is energized

2
by a storage battery 8 or other suitable source of direct current. The circuit, including the solenoid 7 and storage battery 8, is opened and closed by a switch, such as 5 the key 9. To the secondary of the transformer 3 is connected any suitable sending apparatus used in space telegraphy, such as a resonant circuit containing inductance 10, capacity 11, and spark gap 12. The conductor 13 serves to ground the inductance, and the conductor 14 adjustably connected thereto leads to the antenna, not shown.

10 The arrangement shown in Fig. 2 is very much similar to that shown in Fig. 1, except that two mercury-vapor devices instead of one are employed, utilizing both half waves of the alternating current. The circuit through device 15 is completed by conductors 16 and 17. The circuit through 20 the device 18 is completed through conductors 19 and 20. Each device is provided with its own starting circuit, both of which are closed and opened simultaneously by a double contact switch 21. The circuit for 25 converting the energy into electromagnetic waves, as illustrated, is the same as that shown in Fig. 1.

As shown in Fig. 3, a single envelop 22, containing a common mercury electrode 23 and two positive electrodes 24, 25, is employed. The electrodes 24 and 25 are connected to a source of energy, such as a compensator 26, the central point of which is connected to the mercury electrode 23 by 30 conductor 27. In circuit with each of the electrodes 24, 25 is included the primary of transformers 28, 29. The secondaries of these transformers are reverse-connected to a common circuit, which is in turn connected to the primary of a step-up transformer 30. The secondary of transformer 30 is connected to a resonant circuit, as described in connection with Fig. 1, for converting the energy into electromagnetic waves. The device 22 is provided with a single starting electrode 31, which similarly to the starting electrodes shown in Figs. 1 and 2, is operated by a storage battery 8, the circuit being interrupted by a key 9.

50 As shown in detail in Fig. 4, the mercury-vapor device consists of a container 32, which has a cover 33 bolted thereon in such a manner as to make an air-tight joint. The cover is separated from the walls of the container 55 by aluminum or copper washers 34, and the two surfaces are firmly drawn together by tightening the nuts 35. Passing through the cover and making an air-tight joint therewith is the positive electrode 5. It is separated from the cover by an insulating fiber bushing 36. The flange 37, consisting of copper or other metal, is welded to the stem 38 of electrode 5. Above the flange 37 is situated a fiber block 39. Above the block

39 is a spring 40, upon which pressure is 65 exerted by the yoke 41, which is attached to the cover 33 by the bolts 42, 43. By the tightening of bolts 42, 43, pressure is transmitted by the spring 40 to the fiber block 39 and flange 37, and in this manner a perfect 70 seal is maintained at this point. The stem 38 does not come in contact with the spring 40 or the yoke 41, and, therefore, the stem 38 is entirely insulated from the metal container. It is surrounded by a sleeve 44 of 75 insulating material, such as porcelain. The insulating washer 36 is protected from the heat of the arc by a lava bushing 45.

The joint of the auxiliary electrode and of cover is somewhat similar to that already 80 described in connection with the main electrode 5. As shown in detail in Fig. 5, the metal parts are insulated from the cover 33 by insulating sleeve 46. Pressure is transmitted from above in a manner exactly similar to that just described in Fig. 4 by a yoke 47, shown in section, bolted to the cover and resting upon a spring 48, also shown in section, which presses upon the fiber block 49 resting upon the top of the magnet frame 50. 90 The magnet frame 50, consisting of magnetic material, is screwed to the core 51. It contains the winding 52. Through the hollow core 51, consisting of non-magnetic material, as nickel steel, slides a core 53 of 95 magnetic iron, to which is tapped a stem 54 with a flange sliding through non-magnetic metal bushing 55. Surrounding this joint is an insulating sleeve 56, which by the aid of the fiber bushing 46 serves to support and 100 hold in place the refractory insulating sleeve 57 surrounding the stem 54 of the plunger. To the top of the plunger core 53 is attached a guide washer 58 of graphite or other suitable material, to which is attached in turn a 105 spring 59 serving to force down the plunger core when the magnet coil 52 is de-energized, and to assume electrical contact between the plunger and the frame. The upward motion of the plunger is arrested by 110 the flange on the stem 54, and its downward motion by the core 53.

The casing 32 is evacuated through tube 60 welded into the wall. The refractory ring 61, consisting of silica or similar refractory substance, floats on the mercury electrode 4, and serves to confine the cathode spot when an arc is running between the electrodes 4 and 5.

The operation of the device described 120 above is as follows: In the system shown in Fig. 1, when the key 9 is depressed the magnet 7 is energized, thus lifting the auxiliary starting electrode 6 out of contact with the mercury electrode 4 and starting an arc 125 maintained by the battery current between the same. The auxiliary arc between the electrodes 6 and 4 renders the space between

electrodes 4 and 5 conductive and starts an arc between the same for the successive half waves of the alternating-current impressed upon transformer 2. Current flows only 5 when its polarity is such as to make the mercury electrode 4 a cathode. Therefore, a pulsating current is supplied to transformer 3, where it is stepped up to a higher potential and is utilized for the production of 10 electromagnetic waves in the well-known manner. When the switch 9 is open the auxiliary arc is broken, and the arc between electrodes 4 and 5 goes out when the impressed voltage falls below the value necessary to maintain the arc. Therefore, by 15 opening and closing the key 9 the operator can make the dot and dash signals of the Morse code, or any other code, the heavy dynamic current being in each case broken by 20 the inherent action of the mercury vapor device without damaging any contacts.

The operation of the system according to Fig. 2 is very much similar; but in this case when the key 21 is closed an auxiliary arc 25 in both the mercury-vapor devices 15 and 18 is started by the lifting of the auxiliary electrodes. Therefore, when the polarity of the current is such as to make the mercury electrode in device 15 cathode, a current will 30 flow through circuits 17 and 16 to the device 15, and when the polarity reverses current will flow through circuits 20 and 19 through the device 18. An alternating current, therefore, is supplied to the transformer 3, 35 where it is stepped up to higher potential and utilized for the production of electromagnetic waves.

Fig. 3 shows the mercury electrode with two coöperating electrodes. When the key 40 9 is closed an auxiliary arc is started between the electrode 31 and the mercury electrode 23, which renders the space within the container conductive, so that the current flows alternately between electrode 23 and 45 electrode 24 during one-half wave of the alternating current, and between electrode 23 and electrode 25 during the other half wave of the alternating current. When a current flows through the primary of transformer 29 during one-half wave of the alternating current, a current is impressed from 50 its secondary upon the primary of transformer 30. During the other half wave, current is flowing through the primary of 55 transformer 28, and is likewise supplied to the primary of transformer 30. It will, therefore, be seen that an alternating current flows during the time the key 9 is depressed through the primary of transformer 60 30. It is delivered at the desired voltage from the secondary of transformer 30 to the resonant sending circuit, which is identical to that shown in Fig. 1. As soon as the auxiliary arc is broken the main arc goes out

when the voltage falls below the minimum 65 voltage necessary to maintain the same.

The action of the spring 59, assisted by gravity, returns the auxiliary starting electrode quickly to the mercury surface, where it remains in readiness to be again lifted, 70 and, therefore, makes the operation of the device quick and positive.

What I claim as new and desire to secure by Letters Patent of the United States, is—

1. The combination of a source of current 75 of considerable energy periodically passing through zero, a vapor electric device included in circuit therewith, means independent of said source for rendering said device conductive at will continuously during desired intervals in accordance with signals to be transmitted, and means for utilizing the current impulses transmitted by said device for the production of signals.

2. In a system of signaling, the combination of a source of current of considerable energy periodically falling to zero, a mercury arc device included in circuit therewith, and means independent of said source for starting an arc and maintaining the arc- 90 ing space conductive during desired intervals in accordance with signals to be conveyed.

3. In a system of signaling, the combination of a source of alternating current of 95 moderate potential and large current value, a mercury vapor device in circuit therewith, a source of direct current of moderate energy, means operative thereby to render said mercury vapor device conductive at will 100 and an oscillation circuit for utilizing the energy transmitted through said device for the production of electromagnetic waves.

4. In a system of signaling, the combination of a source of periodic current, a vapor 105 electric device included in circuit therewith, electrodes in said device for maintaining an auxiliary arc, a local circuit carrying current of small energy to sustain said auxiliary arc and means in said local circuit 110 for controlling the supply of current in accordance with signals to be transmitted.

5. In a signaling system, the combination of a source of alternating current, a vapor 115 electric device having a vaporizable cathode, and a main anode, a supplemental electrode urged into contact with the cathode, a source of current connected to the supplemental electrode and cathode, and means for withdrawing the supplemental electrode 120 from the cathode, during intervals variable at will thereby striking an arc to render the space in the vapor device conductive during said intervals.

6. In a system of signaling, the combination of a source of periodic current, a source of direct current, a vapor electric 125 device having main electrodes and a sup-

plemental anode, current connections for the main electrodes having an amount of reactance insufficient to secure the overlap of current waves requisite to maintain an arc, connections for the supplemental anode to the direct current source and a switch for completing the direct current circuit to initiate an arc for the supplemental anode

for periods varying in duration in accordance with the signals to be conveyed.

In witness whereof, I have hereunto set my hand this 27th day of July, 1909.

HARRY F. PERKINS.
